UNITED STATES PATENT OFFICE.

HANS RUPPERT, OF FUERTH, GERMANY, ASSIGNOR TO LEONHARD FRIEDRICH BERGDOLT, OF MUNICH, GERMANY.

DRAW-HOOK FOR HARNESS OR THE LIKE.

SPECIFICATION forming part of Letters Patent No. 790,317, dated May 23, 1905.

Application filed April 11, 1904. Serial No. 202,683.

To all whom it may concern:

Be it known that I, HANS RUPPERT, locksmith, whose residence is Simonstrasse 7, Fuerth, Bavaria, in the Empire of Germany, have invented certain new and useful Improvements in Detachable Unions for Harness or the Like; and I do hereby declare the following to be a full, clear, and exact description of the invention, such as will enable others skilled in the art to which it appertains to make and use the same.

My invention relates to improvements in detachable unions for harness and the like, and has for its object the provision of a union whereby the separable members are at all times locked, the said members being also normally prevented from becoming disconnected. Draw hooks and eyes of this type have been so constructed that accidental disconnection under normal conditions could be prevented; but such hooks have not heretofore been so constructed that separable members were held in operative positions.

The object of my invention is to provide a detachable union whereby the separable parts or members are not only prevented from becoming accidentally disconnected, but are maintained in operative alignment. Thus in my improved device the connective union can never be broken, because of the fact that the members have been swung out of an operative position and are made to sustain their load in such non-operative position.

My invention will be more fully described in connection with the accompanying drawings and will be more particularly pointed out in the appended claims.

In the drawings, Figure 1 shows in side elevation one member of the detachable union adapted for direct attachment with the whiffletree or similar parts. Fig. 2 is a sectional view of the parts shown in Fig. 1, also illustrating in connection therewith the companion member of the union in the position in which it is placed when the parts are secured together. Fig. 3 is a detail view of the hook member of the union. Fig. 4 is a plan view of the parts, showing them in an operative position. Fig. 5 is a view in side elevation, showing the parts in the same position illus-

trated in Fig. 4. Fig. 6 is a view of a modified form of hook. Fig. 7 is a plan view showing the application of my improved hook in connection with a harness.

Like parts are designated by similar characters of reference throughout the different figures of the drawings.

My invention comprises generally a slotted member *a*, which, as shown, is adapted to be secured to the end of a whiffletree or the terminals or connectible parts of a harness and which will hereinafter be referred to as the "eye" member. The other or companion of the union consists, as shown, of a hook-shaped bar of metal or like material.

In the application of my invention as shown in Fig. 7 the eye member *a* is secured to the end of a whiffletree, while the hook member is secured to one end of a rope tug.

It will be understood that the invention is capable of various applications to a harness and that I do not wish to be limited to this particular application.

As shown, the eye member *a* is formed of a single strip or length of sheet metal which is bent upon itself in a manner to bring the ends into contact throughout approximately three-fourths of their length. The remaining or middle portion of the strip is spread in a manner to form a closed loop adapted for direct attachment to the whiffletree. This is a feature of decided practical and commercial importance, since it does away with the necessity of providing a separate and distinct member for securing this portion of the union in place. The ends of the strip of metal of which the eye member of the union is formed are provided with elongated slots adapted when the said member is collapsed to bring the slots of the respective ends into register, thereby forming a single elongated slot extending substantially throughout the length of the eye end of the member. The said slot throughout a greater portion of its length is uniform in size and width and at its inner end is provided with an enlarged and preferably circular portion.

The hook member comprises generally a flat hook-shaped body *c*, the tail of which is provided with an attaching-eye, said hook

being substantially equal in thickness to the width of the slot d . Said flat portion of the hook is sufficiently loose in the slot d to permit the member to be attached, but does not 5 permit the hook c to rotate therein or to assume other than a parallel or operative position. Thus it will be seen that if the tug becomes slack and the hook is forced into a retracted position, so that it engages the inner end b of the slot, the flat portion of the hook will still be in engagement with the reduced portion of the slot d and will be held 10 in a position of operative union. The hook is provided with a cylindric portion h near its outer end, which is preferably of sufficient 15 size to rotate freely in the reduced end d , thereby permitting the hook to be inserted and withdrawn from the eye. The outer end of said hook is provided with a knob or 20 head f , which, as shown, is ovoid in form and is adapted to fit snugly in the part b of the slot.

By reference to Fig. 2 it will be seen that when the detachable members of the union 25 are being connected the hook is brought into a position generally at right angles to the loop, the head or knob f being inserted through the enlarged portion b of the slot in a manner to bring the cylindric portion h in a position 30 of register with the reduced end d . It will be noted that the flat portion of the hook could not be brought into register with the reduced end d , as said hook is at this time occupying an angular position not a position of alinement 35 with the slot in said eye member. When the hook is moved outwardly, so that the part h occupies an extreme and opposite position in the slot, the hook c may be turned a sufficient distance to bring the flat portion into a 40 registering position with said slot. The hook c will then be in a position to be engaged with the eye, as shown in Figs. 4 and 5, and any oscillating movement of the hook tending to disconnect the same from the eye will be prevented by reason of the fact that the diameter 45 of the knob f exceeds the width of the slot d , and its oblong construction will prevent its withdrawal through the enlarged end b . It will thus be seen that after the hook and eye 50 are brought into a position of operative union it will not only be impossible to unlock them, (excepting as shown in Fig. 2,) but it will also be impossible to twist or turn them out of operative alinement.

55 It will be seen from the foregoing that my invention as herein shown comprises a draw-hook adapted to perform its function in an effective manner and, being composed of two parts, may be very cheaply constructed.

60 While I have herein shown and described a single embodiment of the invention, I do not wish to be limited thereto, as it will be obvious that departures may be readily made therefrom without departing from the spirit 65 of the invention. Therefore

What I claim, and desire to secure by Letters Patent, is—

1. A detachable union comprising a slotted member, the slot having an enlarged and a reduced portion and being uniform in size 70 throughout its reduced portion, a hook provided with a flat body portion fitting non-rotatively in the reduced portion of said slot, said hook having on one end an ovoid knob or head capable of passing through the enlarged portion of said slot said head exceeding in diameter the reduced portion of said slot, said hook having an intermediate cylindric portion uniting said knob and flat body portion and reduced in size with respect 75 to said knob, said intermediate cylindric portion fitting snugly within the reduced portion of said slot and being capable of rotating and moving back and forth therein, said intermediate portion permitting the flat 80 body portion of the hook to be swung into and out of alinement with said slotted member.

2. A detachable union comprising a slotted member, the slot having an enlarged and a reduced portion, a hook provided with a flat body portion fitting non-rotatively in the reduced portion of said slot and having on one end a knob or head capable of passing through the enlarged portion of the slot, said 90 hook having an intermediate portion uniting said knob and flat body portion, said intermediate portion being reduced with respect to said knob and capable of passing back and forth in the reduced portion of said slot, said 95 intermediate portion permitting the flat body portion of said hook to be swung into and out of alinement with the slotted member.

3. A detachable union comprising a member formed of a single piece of sheet metal the 105 ends thereof being bent together in a manner to form a loop portion at one end of said member, the said ends being slotted and united together in a manner to bring the slots of each end in register to form a single slot in 110 said member, said slot being enlarged at one end and being uniformly reduced throughout the remainder of its length, a hook provided with a flat body portion fitting non-rotatively in the reduced portion of said slot, 115 said flat portion of the hook maintaining the same in parallel relation with said slot and having on its hooked end an ovoid knob or head capable of passing through the enlarged portion of said slot, said head exceeding in diameter the reduced portion of said slot, said hook having an intermediate cylindric portion uniting said knob and flat body portion of the hook and reduced in size with 120 respect to said knob, said intermediate cylindric portion fitting snugly within the reduced portion of said slot and being capable of rotating and of moving back and forth therein, said intermediate portion permitting the flat body portion of the hook to be swung into 125 130

and out of parallel relation with said slotted member.

4. A detachable union comprising a member formed of a single piece of sheet metal the 5 ends thereof being bent together to form an open loop at one end of said member, the said ends being slotted and united in a manner to bring the slots of each end in register to form a single slot having an enlarged and 10 reduced portion, a hook provided with a flat body portion fitting non-rotatively in the reduced portion of said slot and having on one end a knob or head capable of passing through the enlarged portion of the slot, said

hook having an intermediate portion uniting 15 said knob and flat body portion said intermediate portion being reduced with respect to said knob and capable of passing back and forth in the reduced portion of said slot, said intermediate portion permitting the flat body 20 portion of said hook to be swung into and out of alignment with the slotted member.

In testimony whereof I affix my signature in presence of two witnesses.

HANS RUPPERT.
